UNITED STATES PATENT OFFICE

ARBA G. WILLIAMSON, OF CARNEGIE, PENNSYLVANIA, ASSIGNOR, BY MESNE ASSIGNMENTS, TO THE UNION SWITCH & SIGNAL COMPANY, OF SWISSVALE, PENNSYLVANIA, A CORPORATION OF PENNSYLVANIA.

TRAIN-CONTROL SYSTEM

Application filed April 18, 1922, Serial No. 555,804. Renewed November 16, 1929.

This invention relates to traffic controlling systems such as are used in connection with trains, the traffic controlling means being either merely signals or retarding or stopping devices or two or more of these combined.

The main object of this invention is to afford continuous control of the train in response to traffic conditions, so that whenever traffic conditions of the track change the control of the train will likewise change, and to do this in such a manner that more than two operating conditions can be imposed on the train. That is, instead of merely, say, "proceed" and "danger" indications, there shall be at least, say, "proceed", "caution" and "danger" indications, given. Also that this shall preferably be accomplished without the use of ramps or contact members along the running rails.

One feature of the invention centers around two pick-up circuits, carried by the train, of different characteristics—one I will call an indirect and the other I will call a direct pick-up circuit. Preferably the indirect pick-up circuit is of the induced current type and preferably the direct pick-up circuit is of the electrostatic type. The two pick-up circuits are responsive to different traffic conditions, and preferably impose different controlling conditions on the train. So far as certain features of the invention are concerned the two pick-up circuits may each include either one or more controlling elements such as amplifiers or rectifiers, but preferably rectifiers of the character shown in Patent No. 1,695,181 of December 11, 1928, are employed. Preferably also the controlling element will be in the form of electron tubes, and by electron tubes I mean both electron tubes, controlled electrically, and electron tubes controlled magnetically and usually known as magnetrons such as are shown in application Ser. No. 495,722, filed November 14, 1930.

Preferably also, when electron tubes are used as controlling elements the pick-up circuits control the grid potential to render it negative by means of a condenser or otherwise under certain operating conditions, and this may change the resistance of a train con-

trolling circuit to a new maintained value so long as certain traffic conditions prevail, or as shown in application Ser. No. 372,567 filed June 21, 1929, the effect of impressing symmetrical pulsations upon the controlling element may be to produce a non-symmetrical resistance in the train controlling circuit and thereby effect train control.

In connection with the above train equipment certain track equipment is used which may, however, vary widely. The rails may for instance have impressed upon them a pulsating current, and by pulsating I mean to include both an alternating or an oscillating current or an interrupted or fluctuating direct current, or when magnetrons are used as controlling elements, a simple uninterrupted direct current may be employed. The track current for influencing the indirect pick-up circuit will flow in both rails, while the track circuit for influencing the direct pick-up circuit is connected to one rail or both rails and ground. Track circuits suitable for use in connection with this invention are disclosed in Patents Nos. 1,664,382 of March 27, 1928, 1,683,222 of September 4, 1928, and application Ser. No. 165,603 filed February 3, 1927, as a continuation in part of application Ser. No. 549,663 filed April 5, 1922. However, the combination of track-way means to supply interrupted or periodically varying current in combination with cab equipment controlled by the influence of such current is not claimed herein but forms the subject matter of applicant's co-pending application Ser. No. 215,318 filed August 25, 1927.

Other features of invention will appear as the specification proceeds.

In the accompanying drawings the invention is shown in a concrete and preferred form in which

Fig. 1 is a diagrammatic view of one form of track circuits that may be used in connection with the invention.

Fig. 2 is a diagrammatic view of a preferred form of train carried circuits embodying the invention.

Fig. 3 is a side elevation, partly broken

away, of a relay that may be used in the train controlling circuit.

Fig. 4 is a top plan view of same.

Fig. 5 is a bottom plan view of the elements of the relay with the neutral armatures omitted.

Fig. 6 is a sectional detail view of a release valve that may be used in connection with my invention.

10 Referring to Fig. 1, 1 and 2 represent the rails of a traffic track divided into blocks, W, X, Y and Z in a manner well understood as by means of insulation 3. 4 and 5 indicate line wires fed by the single frequency generator G. Associated with each block is 15 a main transformer indicated by T_w , T_x , and T_y and the secondary 6 of each of those transformers is connected by means of conductors 7 and 9 with primary 8 of a track 20 transformer indicated variously as N_w , N_x and N_y . Secondary 13 of the track transformer is connected by means of leads 16 and 17 with rails 1 and 2 thereby supplying current to both of said rails of a given block. 25 These elements together with a relay such as r_w , r_y or r_z constitute the ordinary track circuit. Connected in parallel with the track transformer is a subsidiary transformer indicated at M_w , M_x and M_y , the primary 11 30 of which is connected by wires 10 and 12 with conductors 7 and 9, and this subsidiary transformer applies a voltage to a circuit connected to one rail and ground, which circuit is as follows: Connected with one side 35 of secondary 18 is a conductor 19, which is grounded, and connected with the other side of secondary 18 is a conductor indicated by wires 20, 23 and 25, the latter connected to lead 16. 15 and 24 indicate impedances, one 40 for the track circuit and the other for the rail and ground circuit. 21, with an exponent indicating its block location, is a circuit breaker interposed in the rail and ground circuit and this circuit breaker is 45 actuated either by signal S of the block in advance or by relay r likewise of the block in advance.

Normally current will flow in the rails of the track circuit fed by track transformer N 50 and a voltage will be applied by secondary 18 along wire 20, circuit breaker 21, wire 23, impedance 24, and wires 25 and 16 to rail 1. The other side of secondary 18 being connected to ground by wire 19, a difference of 55 potential is created between rail and ground (zero earth potential). It will be understood that rail 1 is not grounded and that it does not have the same potential (zero) as the earth because it is insulated to a certain 60 extent by the ballast. When, therefore, a train as K' enters a block under normal conditions, the indirect and direct pick-up circuits carried by the train will both be influenced. The effect of the presence of a train as at K in 65 block Z on the block in rear Y will be readily

understood. Such train will short circuit the track circuit thereby actuating signal S_z or deenergizing relay r_z and will thereby move circuit breaker 21_y against stop 22_y thereby rupturing the rail and ground circuit of block Y and a train in block Y would therefore not have its direct pick-up circuit influenced, but would nevertheless have its indirect pick-up circuit influenced because the track circuit of block Y is not affected by the presence of a train in block Z. Should a second train advance from block Y into the occupied block Z it is clear that such second train would not have either its indirect or its direct pick-up circuits influenced.

Referring now generally to Fig. 2 the exemplification of train equipment there shown for use in connection with my invention is as follows:

The controlling elements of the two pick-up circuits are here shown as two electrically controlled electron tubes E and E'. I denotes a cab indicator having differently colored lights for different traffic conditions. R and R' indicate two polarized relays controlled by the pick-up circuits and controlling the indicator lights. D is a dynamotor which receives say thirty-two volts in its infeed circuit over wires 51 and 52 conveniently leading from the headlight generator, that is, current flows from the headlight generator, along wire 52, through the motor end of dynamotor D and from the latter by way of brush 37 to wire 51 and thence to headlight generator. Dynamotor D supplies from its generator end say 350 volts to the plate-filament circuits, said circuits to be pointed out later; and by means of third brush 27, properly positioned on the commutator of the motor end of D, about eight volts are supplied to the filament circuits of the electron tubes, said circuits also to be pointed out later. The indicator lights are fed directly from wires 51 and 52. The train equipment may further consist of brake controlling means consisting here generally of magnet valve M, brake valve B and release valve R_v. As here shown, the construction of these parts is as follows:

When magnet valve M is energized, valve 127 is 115 in its closed position and valve 128 is in its open position thereby permitting pressure to flow from the brake pipe, past valve 128 and through port 129 into piston chamber 130 of brake valve B. This pressure will force piston 131 to the right in Fig. 2, thereby closing valve 133 which stops the flow of pressure from the brake pipe to exhaust pipe 134 and port 135 of release valve R_v. When magnet valve M is deenergized, air pressure and spring 129^a seat valve 128 and open valve 127 thereby stopping the flow of pressure from the brake pipe to port 129. The pressure accumulated in chamber 130 will now be exhausted through port 129, past valve 127 and 130

out through port 136, the action of spring 132 moving piston 131 to the left in Fig. 2. By this action valve 133 is opened so as to permit free flow from the brake pipe to exhaust pipe 134 and release valve port 135. If desired, release valve R_v can be so arranged that it is accessible to the engineer and, if such be the case, he can then turn release valve into the position shown in Fig. 6, thereby stopping application of the brakes. The engineer may then proceed under the caution visual signal to be described later. When magnet M is again energized, piston 131 will again be moved to the right in Fig. 2 and member 137, movable with said piston, will then automatically force handle 138 and thereby release valve R_v into the position shown in Fig. 2, so that when the magnet is again de-energized the brakes will be applied.

20 Polarized relays R and R' may be alike and are of the polarized direct-current type. The description of one of these relays will suffice for both.

Referring to Figs. 3, 4 and 5, the coils 90 and 91 of the relays are on spools which slip over cores 92 and 93, said cores having pole pieces 94 and 95 magnetically connected at the top by soft iron piece 96. Neutral armature 55 (in the case of relay R) is pivoted at 55a and is attracted to the poles whenever sufficient current flows in the coils. A permanent magnet 97 fits at its top into soft iron piece 96 and carries at its bottom soft iron piece 98 to which latter is pivoted at 58a, so as to swing freely, a polarized armature 58 (in the case of relay R). Assuming that the top of permanent magnet 97 is positive and that its bottom end is negative, then both poles 94 and 95 will be positive and both ends of polarized armature 58 will be negative, and, as the air gap between 58 and 94 is greater than the air gap between 58 and 95, armature 58 will swing into the position indicated in Fig. 5 against contact 72 (in the case of relay R) when no current flows in the coils. Now if a current of proper value so flows in coils 90 and 91 as to render pole piece 94 positive and pole piece 95 negative, then armature 58 will be attracted by pole piece 94 and will swing into engagement with contact 59 (in the case of relay R). If, however, current of greater strength than previously assumed is caused to flow through coils 90 and 91 then, due to the electro-magnetic action, as distinguished from the polar action in the coils, and to the difference in the air gap before mentioned, armature 58 will swing into its original position as shown in Fig. 5. Thus the armature will occupy the same position when no current is present in coils 90 and 91 as it does when a strong current energizes said coils, and will occupy another position when a weak current energizes said coils. The object of this will be pointed out later.

The specific form here shown (Fig. 2) of train carried circuits will now be described. The indirect pick-up circuit, in this case an induced-current circuit, of electron tube E is as follows: coil 28, energized by the current impressed between the two rails of the track, conductor 29, condenser 30, grid 31 of electron tube E , filament 32 of electron tube E , conductor 34 back to coil 28. 35 is a tuning condenser to tune the circuit to the proper frequency of the track circuit. The direct pick-up circuit of electron tube E' is as follows: grid 84 of tube E' , filament 38 of tube E' , wire 82, condenser 81 and wire 80 back to grid. 83 is a wire connecting this circuit with a part, say one of the axles, of the train so as to be influenced by the rail circuit impressed between rail and ground. The filaments of the two electron tubes are connected in parallel with dynamotor D as follows: from third brush 27, by wire 36, to filament 32 of tube E , by wire 33, back to brush 37; and from third brush 27, by wire 36, wire 39, to filament 38 of electron tube E' , by wire 40, wire 51 back to brush 37. The plate circuits of the two tubes are likewise connected in parallel and are as follows: from brush 43, by wire 44, relay R , wire 45, plate 42 of tube E , filament 32 of tube E , wire 33, wire 46 and back to brush 47; and from brush 43, by wire 49, to relay R' , by wire 50, to plate 48 of tube E' , filament 38 of tube E' , wire 40, wire 51, wire 46 back to brush 47. The proceed cab indicator light circuit is as follows, all of the lights receiving current from the thirty-two volt supply coming from the head light generator. Starting from wire 52, along wire 54, neutral armature 55, contact 56, wire 57, polarized armature 58, contact 59, wire 60, neutral armature 61, contact 62, wire 63, polarized armature 64, contact 65, wire 66, proceed light 53 and common return wire 67 back to wire 51. Under caution conditions, that is with the rail circuit between rail and ground ruptured, the circuit will be as follows: over the same circuit as previously described in connection with the proceed light up to polarized armature 64 of relay R' , then to contact 69, wire 70, to caution light 68 and then to common return wire 67. The danger indicator light receives current under several conditions as follows: When polarized armature 58 is in its left-hand position against contact 72, then by way of wire 73 to danger light 71 and thence to common return wire 67. When neutral armature 55 is down against contact 74, then by wire 75, to wire 73, danger light 71 and common return wire 67. When neutral armature 55 and polarized armature 58 of relay R are in the position shown in Fig. 2, but neutral armature 61 is down against contact 76, then by wires 77 and 73 to danger light 71 and thence to common return wire. In the form of the invention here

shown, magnet M is in parallel with the proceed cab light by reason of wire 78 leading from wire 66 to magnet M and thence by wire 79 to common return wire 67.

5 The inductive pick-up circuit controls the plate circuit of tube E in the following manner: Plate 42 is positive, grid 31 is of the same potential as filament 32 and the filament is heated. Thus when no current flows in the induced pick-up circuit a current in one direction will flow in the plate circuit and through relay R, and this current will be the full value of current supplied by the dynamotor. We will assume this value to be 1.0. 10 When current flows in that rail circuit which includes the two running rails, an alternating current will be induced in the inductive pick-up circuit. When the alternating voltage thus produced is applied between the grid 15 and filament, the alternating current is rectified into a direct current, current flowing only when the induced voltage makes the grid positive. In other words, the space between the grid and the filament constitutes a rectifier, one of the swings of the alternating current being suppressed. If condenser 30 were what is generally called a leaky condenser, that is, provided with a resistance, it would be charged when the rectified current is flowing 20 and discharge during the suppression of the swing of the current in the other direction and the result would be to render the grid potential alternately positive and negative thus producing a current in the plate circuit having a rise and fall. Condenser 30, 25 however, is not a leaky condenser, that is, it will not discharge, during the suppressed swing, the charge built up during the effective swing of the current. The result is, 30 therefore, that a charge is gradually built up on the condenser thereby rendering the grid negative with respect to the filament by an amount equal to the alternating voltage induced in coil 28, and the grid is maintained 35 negative so long as current flows. If current ceases to flow in coil 28, the condenser will gradually discharge.

50 The effect of rendering and maintaining the grid negative during the flow of current in the pick-up circuit is to choke down the value of the current in the plate circuit. It virtually increases the resistance of the plate circuit to a new maintained value. The original value of the current in the plate circuit 55 we assumed to be 1.0, and we will assume that 0.4 represents the value of the choked-down current.

50 The effect of the grid circuit of tube E' upon the plate circuit of said tube is substantially the same as that described in connection with the plate circuit of tube E although the action is somewhat different. By means of direct current generator D, there is established between filament 38 and plate 48 a 65 steady difference of potential under the in-

fluence of which a steady current flows through the tube from 48 to 38. This current thus establishes a definite potential between grid 84 and filament 38 which is, however, considerably less than the difference in potential between the plate and filament. This potential we may call the free grid potential. By connecting the grid circuit directly through wire 83 with the wheels and track, the potential of the grid with respect to ground is caused to alternate by an amount corresponding to the voltage impressed between rail and ground. As there is nothing to cause a corresponding variation in the potential of the filament relative to ground, nor in the plate with respect to the filament, a charge is gradually built up in the grid circuit by the variation in potential of the grid with respect to the free grid potential. It must be understood that the ground serves, 70 in this direct pick-up circuit, as one plate of a coupling condenser operative between the cab and track circuits and, following the customary usage, the potential of the ground will be taken as the zero of potential with 75 respect to all the others in the system. In this case likewise the grid is rendered negative and the plate circuit current is choked down just as in tube E; and this notwithstanding the change in the free grid potential 80 due to the reduction of the plate-circuit current. As in the case of tube E, let us assume that the full value of the plate circuit current is 1.0. This value is maintained when the grid is connected to the rail and no voltage is 85 impressed between rail and ground; and, under these conditions, the tube is quickly brought to an equilibrium, the potential of the filament with respect to grid and ground being approximately equal to the free grid 90 potential. When now an alternating voltage is applied between rail and ground, the potential of the grid alternates with respect to its original value, condenser 81 is quickly charged, and the mean potential of the grid 95 relative to the free grid potential (and hence to the filament potential) is lowered. The plate circuit current is therefore choked down to a value of, say, 0.4. Condenser 81 is not a 100 leaky condenser in that it does not discharge during a swing in one direction an amount equal to the charge accumulated during the 105 swing in the other direction. However, when the alternations cease in the track circuit between rail and ground, the condenser gradually discharges and the free grid potential is restored. It is not absolutely necessary to have a condenser like 81 in the grid circuit as I have found that the grid circuit as 110 a whole may have such capacity as to virtually constitute a condenser.

Relays R and R' have their polarized armatures 58 and 64 so arranged that the train 115 controlling circuits will be closed at 72 and 69 when no current is flowing in the relays 120 125 130

or when current of a value of say more than 0.8 is flowing. When, however, a current of a value of, say, 0.4 to 0.8 is flowing, contact points 59 and 65 will be closed by the 5 polarized armatures. The neutral armatures may really be disregarded since they constitute merely an additional means of breaking the circuits in case of failure in the plate or filament circuits.

10 It will now be understood that, when a train is traveling through a block which is not occupied by another train and no train is in the block in advance, voltage will be applied in the rail circuits between the two 15 rails and also between one rail and ground. Consequently the value of the plate-circuit current of the two electron tubes is reduced to 0.4 and relays R and R' will therefore hold 20 armatures 58 and 64 in the position shown in Fig. 2 thereby showing a proceed indication at 53 in the cab and holding magnet M energized. Should, however, a train be present in the block in advance, then no voltage will be applied between rail and ground 25 and consequently the plate-circuit current of tube E' will not be choked down but will be of the value of 1.0. The effect of this is to cause relay R' to flip armature 64 to the left thereby destroying the circuit through 30 proceed light 53 and magnet M and establishing a circuit through caution light 68. The brakes will therefore be applied unless the engineer moves release valve R_v to position Fig. 6 in which case he should proceed 35 with caution. If the train now enters a block already occupied by another train, then the induced-current pick-up circuit will not be energized and consequently the value of the plate-circuit current of tube E will be re- 40 stored to 1.0 and relay R will flip armature 58 into left hand position thereby destroying the circuit through caution light 68 and establishing a circuit through danger light 71. Magnet M will remain deenergized. 45 The effect of breaking a wire in the plate-circuits will be to deenergize relay R or R' as the case may be which, as I have shown, has the same effect upon armatures 58 and 64 as when said relays were fully energized; 50 that is, the train would get a danger indication.

It will be obvious from the foregoing that whenever there is any change in traffic conditions such change will immediately be reflected in operating conditions imposed upon the train.

I claim:

1. A train control system including: traffic rails, a circuit including both rails, a second circuit including rail and ground, a car, an indirect pick-up circuit, on the car, under the control of the first circuit, and a direct pick-up circuit also on the car and controlled by the second circuit.

65 2. A train control system including: traffic

rails, a circuit including both rails, a second circuit including rail and ground, a car, an indirect pick-up circuit, on the car, under the control of the first circuit, a direct pick-up circuit also in the car and controlled by the second circuit, and traffic controlling means, on the car, under the control of the two pick-up circuits.

3. A train control system including: traffic rails divided into blocks, a circuit including both rails of a block, a second circuit including rail and ground in each block, one of said circuits being controlled continuously by traffic conditions of another block, a car, an indirect pick-up circuit, on the car, controlled by the first circuit, and a direct pick-up circuit also on the car and influenced by the second circuit.

4. A train control system including: traffic rails divided into blocks, a circuit including both rails of a block, a second circuit including rail and ground in each block and continuously controlled by traffic conditions of another block, a car, an indirect pick-up circuit, on the car, controlled by the first circuit, and a direct pick-up circuit also on the car and influenced by the second circuit.

5. A train control system including: traffic rails divided into blocks, a circuit including both rails of a block, a second circuit including rail and ground in each block, one of said circuits being controlled continuously by traffic conditions of another block, a car, an indirect pick-up circuit, on the car, controlled by the first circuit, a direct pick-up circuit also on the car and influenced by the second circuit, and traffic controlling means on the car under the control of the two pick-up circuits.

6. A train control system including: traffic rails divided into blocks, a circuit including both rails of a block, a second circuit including rail and ground in each block and continuously controlled by traffic conditions of another block, a car, an indirect pick-up circuit, on the car, controlled by the first circuit, a direct pick-up circuit also on the car and influenced by the second circuit, and traffic controlling means on the car under the control of the two pick-up circuits.

7. A train control system including: traffic rails divided into blocks, a circuit including both rails in series, a second circuit, connected to ground at one side and to at least one of the rails at its other side, for maintaining voltage above ground potential on at least one of said rails, a car, an indirect pick-up circuit, on the car, under the control of the first circuit, and a direct pick-up circuit also on the car and controlled by the second circuit.

8. A train control system including: traffic rails divided into blocks, a circuit including both rails in series, a second circuit, connected to ground at one side and to at least

- one of the rails at its other side, for maintaining voltage above ground potential on at least one of said rails, a car, an indirect pick-up circuit, on the car, under the control of the first circuit, a direct pick-up circuit also on the car and controlled by the second circuit, and traffic controlling means, on the car, under the control of the two pick-up circuits.
9. A train control system including: traffic rails divided into blocks, a circuit including both rails in series, a second circuit, connected to ground at one side and to at least one of the rails at its other side, for maintaining voltage above ground potential on at least one of said rails, one of said circuits being controlled continuously by traffic conditions of another block, a car, an indirect pick-up circuit, on the car, under the control of the first circuit, and a direct pick-up circuit also on the car and controlled by the second circuit.
10. A train control system including: traffic rails divided into blocks, a circuit including both rails in series, a second circuit, connected to ground at one side and to at least one of the rails at its other side, for maintaining voltage above ground potential on at least one of said rails, and continuously controlled by traffic conditions of another block, a car, an indirect pick-up circuit, on the car, under the control of the first circuit, and a direct pick-up circuit also on the car and controlled by the second circuit.
11. A train control system including: traffic rails divided into blocks, a circuit including both rails in series, a second circuit, connected to ground at one side and to at least one of the rails at its other side, for maintaining voltage above ground potential on at least one of said rails, one of said circuits being controlled continuously by traffic conditions of another block, a car, an indirect pick-up circuit, on the car, under the control of the first circuit, a direct pick-up circuit also on the car and controlled by the second circuit, and traffic controlling means, on the car, under the control of the two pick-up circuits.
12. A train control system including: traffic rails divided into blocks, a circuit including both rails in series, a second circuit, connected to ground at one side and to at least one of the rails at its other side, for maintaining voltage above ground potential on at least one of said rails, and continuously controlled by traffic conditions of another block, a car, an indirect pick-up circuit, on the car, under the control of the first circuit, a direct pick-up circuit also on the car and controlled by the second circuit, and traffic controlling means, on the car, under the control of the two pick-up circuits.
13. A train control system including: a traffic track, divided into blocks, a track circuit connected to ground on one side and to at least one traffic rail on the other side to maintain a difference of potential between rail and ground, a car, and a pick-up circuit on the car electrostatically coupled to the track circuit.
14. A train control system including: a traffic track, divided into blocks, a track circuit connected to ground on one side and to at least one traffic rail on the other side to maintain a difference of potential between rail and ground, a car, a pick-up circuit on the car electrostatically coupled to the track circuit, and traffic controlling means on the car under the control of the pick-up circuit.
15. A train control system including: a traffic track divided into blocks, a track circuit connected to ground on one side and to at least one traffic rail on the other side to maintain a difference of potential between rail and ground, a car, a pick-up circuit on the car electrostatically coupled to the track circuit, and means for controlling the track circuit in response to traffic conditions of another block.
16. A train control system including: a traffic track divided into blocks, a track circuit connected to ground on one side and to at least one traffic rail on the other side to maintain a difference of potential between rail and ground, a car, a pick-up circuit on the car electrostatically coupled to the track circuit, traffic controlling means on the car under the control of the pick-up circuit, and means for controlling the track circuit in response to traffic conditions of another block.
17. A train control system including: a traffic track, a track circuit connected to ground on one side and to at least one traffic rail on the other side, and a pick-up circuit on the car so coupled to the track circuit that the ground serves as one plate of a coupling condenser.
18. A train control system including: a traffic track, a track circuit connected to ground on one side and to at least one traffic rail on the other side, a pick-up circuit on the car so coupled to the track circuit that the ground serves as one plate of a coupling condenser, and traffic controlling means on the car under the control of the pick-up circuit.
19. A train control system including: a traffic track, a track circuit connected to ground on one side and to at least one traffic rail on the other side, a pick-up circuit on the car so coupled to the track circuit that the ground serves as one plate of a coupling condenser, and means for controlling the track circuit in response to traffic conditions of another block.
20. A train control system including: a traffic track, a track circuit connected to ground on one side and to at least one traffic rail on the other side, a pick-up circuit on the car so coupled to the track circuit that the ground serves as one plate of a coupling condenser.

- denser, traffic controlling means on the car under the control of the pick-up circuit, and means for controlling the track circuit in response to traffic conditions of another block.
5. 21. A train control system including: traffic rails, a circuit including both rails, a second circuit including rail and ground, a car, an indirect pick-up circuit, on the car, under the control of the first circuit, a direct pick-up circuit also in the car and controlled by the second circuit, and two electron tubes one under the control of one and the other under the control of the other pick-up circuit. 70
10. 22. A train control system including: traffic rails, a circuit including both rails, a second circuit including rail and ground, a car, an indirect pick-up circuit, on the car, under the control of the first circuit, a direct pick-up circuit also on the car and controlled by the second circuit, and two electron tubes one under the control of one and the other under the control of the other pick-up circuit. 75
15. 23. A train control system including: traffic rails, a circuit including both rails, a second circuit including rail and ground, a car, an indirect pick-up circuit, on the car, under the control of the first circuit, a direct pick-up circuit also on the car and controlled by the second circuit, and two rectifiers, one under the control of one and the other under the control of the other pick-up circuit. 80
20. 24. A train control system including: traffic rails, a circuit including both rails, a second circuit including rail and ground, a car, an indirect pick-up circuit, on the car, under the control of the first circuit, a direct pick-up circuit also on the car and controlled by the second circuit, and two electron tubes, the potential of the grid of one tube controlled by one pick-up circuit and the potential of the grid of the other tube controlled by the other pick-up circuit. 85
25. 25. A train control system including: traffic rails divided into blocks, a circuit including both rails of a block, a second circuit including rail and ground in each block, one of said circuits being controlled by traffic conditions of another block, a car, an induced-current pick-up circuit, on the car, energized by the first circuit, and a direct pick-up circuit also on the car and influenced by the second circuit. 90
30. 26. A train control system including: traffic rails divided into blocks, a circuit including both rails of a block, a second circuit including rail and ground in each block and controlled by traffic conditions of another block, a car, an induced-current pick-up circuit, on the car, energized by the first circuit, and a direct pick-up circuit also on the car and influenced by the second circuit. 95
35. 27. A train control system including: traffic rails divided into blocks, a circuit including both rails of a block, a second circuit including rail and ground in each block, one of said circuits being controlled continuously by traffic conditions of another block, a car, an induced-current pick-up circuit, on the car, energized by the first circuit, a direct pick-up circuit also on the car and influenced by the second circuit. 100
40. 28. A train control system including: traffic rails divided into blocks, a circuit including both rails of a block, a second circuit including rail and ground in each block and controlled continuously by traffic conditions of another block, a car, an induced-current pick-up circuit, on the car, energized by the first circuit, and a direct pick-up circuit also on the car and influenced by the second circuit. 105
45. 29. A train control system including: traffic rails, a circuit including both rails, a second circuit including rail and ground, a car, an induced-current pick-up circuit, on the car, energized by the first circuit, a direct pick-up circuit also on the car and influenced by the second circuit, and two electron tubes, one under the control of one and the other under the control of the other pick-up circuit. 110
50. 30. A train control system including: traffic rails, a circuit including both rails, a second circuit including rail and ground, a car, an induced-current pick-up circuit, on the car, energized by the first circuit, a direct pick-up circuit also on the car and influenced by the second circuit, and two rectifiers, one under the control of one and the other under the control of the other pick-up circuit. 115
55. 31. A train control system including: traffic rails, a circuit including both rails, a second circuit including rail and ground, a car, an induced-current pick-up circuit, on the car, energized by the first circuit, a direct pick-up circuit also on the car and influenced by the second circuit, and two electron tubes, the potential of the grid of one tube controlled by one pick-up circuit and the potential of the grid of the other tube controlled by the other pick-up circuit. 120
60. 32. A train control system including: traffic rails divided into blocks, a circuit including both rails of a block, a second circuit including rail and ground in each block, one of said circuits being controlled by traffic conditions of another block, a car, an induced-current pick-up circuit, on the car, energized by the first circuit, a direct pick-up circuit also on the car and influenced by the second circuit, and two electron tubes, one under the control of one and the other under the control of the other pick-up circuit. 125
65. 33. A train control system including: traffic rails divided into blocks, a circuit including both rails of a block, a second circuit including rail and ground in each block, one of said circuits being controlled by traffic conditions of another block, a car, an induced-current pick-up circuit, on the car, energized by the first circuit, a direct pick-up circuit also on the car and influenced by the second circuit. 130

second circuit, and two rectifiers, one under the control of one and the other under the control of the other pick-up circuit.

34. A train control system including: traffic rails divided into blocks, a circuit including both rails of a block, a second circuit including rail and ground in each block, one of said circuits being controlled by traffic conditions of another block, a car, an induced-current pick-up circuit, on the car, energized by the first circuit, a direct pick-up circuit also on the car and influenced by the second circuit, and two electron tubes, the potential of the grid of one tube controlled by one pick-up circuit and the potential of the grid of the other tube controlled by the other pick-up circuit.

35. A car carried train control system including: two electron tubes, a source of power, two plate circuits arranged in parallel, each circuit including the plate and filament of a tube, fed by said source of power, two filament circuits, one for each tube, also arranged in parallel and fed by said source of power, two independently controlled relays, one included in each plate circuit, and a traffic controlling circuit under the control of both relays.

36. A car carried train control system including: two electron tubes, a source of power, two plate circuits arranged in parallel, each circuit including the plate and filament of a tube, fed by said source of power, two filament circuits, one for each tube, also arranged in parallel and fed by said source of power, two independently controlled relays, one included in each plate circuit, a traffic controlling circuit under the control of both relays, and feed wires connected to said traffic controlling circuit and connected to the source of power.

37. A car carried train control system including: two electron tubes, a source of power, two plate circuits arranged in parallel, each circuit including the plate and filament of a tube, fed by said source of power, two filament circuits, one for each tube, also arranged in parallel and fed by said source of power, two independently controlled relays, one included in each plate circuit, a traffic controlling circuit under the control of both relays, and independent pick-up circuits for controlling the grid of each tube.

38. A car carried train control system including: two electron tubes, a source of power, two plate circuits arranged in parallel, each circuit including the plate and filament of a tube, fed by said source of power, two filament circuits, one for each tube, also arranged in parallel and fed by said source of power, two independently controlled relays, one included in each plate circuit, a traffic controlling circuit under the control of both relays, feed wires connected to said traffic controlling circuit and connected

to the source of power, and independent pick-up circuits for controlling the grid of each tube.

39. A car carried train control system including: two electron tubes, a source of power, two plate circuits arranged in parallel, each circuit including the plate and filament of a tube, fed by said source of power, two filament circuits, one for each tube, also arranged in parallel and fed by said source of power, two independently controlled relays, one included in each plate circuit, a traffic controlling circuit under the control of both relays, an induced-current pick-up circuit controlling the grid of one tube, and a direct pick-up circuit controlling the grid of the other tube.

40. A car carried train control system including: two electron tubes, a source of power, two plate circuits arranged in parallel, each circuit including the plate and filament of a tube, fed by said source of power, two filament circuits, one for each tube, also arranged in parallel and fed by said source of power, two independently controlled relays, one included in each plate circuit, a traffic controlling circuit under the control of both relays, feed wires connected to said traffic controlling circuit and connected to the source of power, an induced-current pick-up circuit controlling the grid of one tube, and a direct pick-up circuit controlling the grid of the other tube.

41. A train control system including: a traffic track arranged in blocks, two train-controlling track circuits for each block each of which includes the traffic track, a train, two train-carried charged circuits each having a normal flow of current of a given value, train-carried pick-up and controlling apparatus to lessen the value of the current in one or both of the charged circuits in response to certain traffic conditions of the track circuits, a circuit closing means under the control of the charged circuits, and train-carried signalling circuits selectively controlled by the said circuit closing means.

42. A train control system including: a traffic track arranged in blocks, trackway train-controlling means for each block which includes the traffic track of the block and which is responsive to traffic conditions in advance, a train, two train-carried charged circuits each having a normal flow of current of a given value, train-carried pick-up and controlling apparatus to lessen the value of the current in one of said charged circuits and not in the other in response to a given traffic condition of the trackway means, a circuit closing means under the control of the charged circuits, and a train-carried signalling circuit held closed by said circuit closing means as long as the current in the one charged circuit is maintained at the lesser

value by the said traffic condition of the track-way means.

43. A car carried train control system including: an electron tube having a plate, grid and filament with circuits therefor, means for rendering the grid negative in potential with respect to the filament to control the flow of current in the plate circuit, an electromagnet controlled by the plate circuit, a permanent magnet, and a car-governing armature controlled jointly by said electro-magnet and said permanent magnet and arranged to assume one given position when the plate circuit is controlled by the negative potential on the grid, and to assume another given position when the plate circuit is not controlled by negative potential on the grid or when the permanent magnet only is active.

44. A car carried train control system including: an electron tube having a plate, grid and filament with circuits therefor, means for rendering the grid negative in potential with respect to the filament to control the flow of current in the plate circuit, an electro-magnet controlled by the plate circuit, a permanent magnet, and a car-governing armature controlled jointly by said electro-magnet and said permanent magnet and arranged to assume one given condition when the plate circuit is controlled by the negative potential on the grid, and to assume another given condition when the plate circuit is not controlled by a negative potential of the grid or when the permanent magnet only is active.

45. A car carried train control system including: an electron tube having a plate, a grid and a filament, a circuit for heating said filament, a receiving circuit for controlling the potential of the grid with respect to the filament, a plate circuit having a current source capable of supplying a direct current flow of a given value in response to a given potential of the grid with respect to the filament, a direct current polarized car governing armature, means under the control of the plate circuit to cause said armature to assume one position in response to the establishing of the current flow of said given value, and to cause said armature to assume a second position in response both to an increase or a decrease in the value of the direct current flowing in the plate circuit with respect to said given value; and means for influencing, under certain conditions, said receiving circuit to create said given potential of the grid with respect to the filament.

46. A car carried train control system including: a car carried receiving circuit, a car carried closed circuit having a source of direct current of a given polarity, a car carried translating means responsive to an alternating current induced in the receiving circuit to establish a given value of the direct current flowing in the closed circuit but not af-

fecting the polarity or continuity of said circuit, a direct current polarized car governing armature, means under the control of the closed circuit to cause said armature to assume one position in response to the establishing of said given value of current in the closed circuit, and to cause said armature to assume a second position in response both to an increase or a decrease in the value of the direct current flowing in the closed circuit with respect to said given value, and a trackway source of alternating current to induce, under certain conditions, an alternating current in the receiving circuit.

47. A train control system including: a train-carried electron tube having a plate, a grid, and a filament with circuits therefor, trackway means to exert an influence, under clear traffic conditions, that determines the potential of the grid with respect to the filament to thereby control the flow of current in the plate circuit, an electro-magnet energized by the flow of current in the plate circuit, a permanent magnet, and a traffic-governing polarized armature, controlled jointly by the influence of the electro-magnet and the permanent magnet, which assumes a clear traffic-governing condition in response to the energization of the electro-magnet that results from the grid potential determined by the influence of the trackway means, and which assumes a danger traffic-governing condition in response to the energization of the electro-magnet that results when the trackway means ceases to exert an influence on the grid potential, or when the permanent magnet only is active in the control of said armature.

48. A train control system including: a train-carried closed circuit having a source of current, a trackway means to exert an influence, under certain traffic conditions, to control the flow of current in the closed circuit, an electro-magnet energized by the flow of current in the closed circuit, a permanent magnet, and a traffic-governing polarized armature, controlled jointly by the influence of the electro-magnet and the permanent magnet, which assumes one traffic-governing condition in response to the energization of the electro-magnet that results from the influence of the trackway means, and which assumes a second traffic governing condition in response to the energization of the electro-magnet that results from the absence of the influence of the trackway means, or when the permanent magnet only is active in the control of said armature.

Signed at Pittsburgh, in the county of Allegheny and State of Pennsylvania, this 6th day of April, 1922.

ARBA G. WILLIAMSON.
